UNITED STATES PATENT OFFICE.

JULIUS BRENZINGER, OF FAIRFIELD, CONNECTICUT.

MACHINE FOR APPLYING A SEAM-PACKING COMPOSITION TO CAN-COVERS.

1,296,474.

Specification of Letters Patent.

Patented Mar. 4, 1919.

Application filed January 10, 1918. Serial No. 211,225.

To all whom it may concern:

Be it known that I, JULIUS BRENZINGER, a citizen of the United States, residing at Fairfield, in the county of Fairfield and State of Connecticut, have invented certain new and useful Improvements in Machines for Applying a Seam-Packing Composition to Can-Covers, of which the following is a specification.

10 It is well known in the art to which this invention appertains that can bodies designed to be headed by what is known as the double-seaming process are first end flanged, and each head or cover is provided with a corresponding flange adapted to be superposed on the body flange when the parts are assembled for the seaming operation, the cover flange generally projecting a slight distance beyond the body flange and the two being 15 intercurled by the seaming operation and the intercurled layers compressed into a substantially solid or air-tight head.

Inherent irregularities in the metal being operated upon and slight and inevitable imperfections in the seaming mechanism render it desirable, if not essential to the best results, that some form of suitable packing be interposed between the intercurled flanges in order to insure an absolutely hermetic 20 seam. Obviously—considering the vast extent of the use of containers of this class and the necessity for comparatively great producing and output capacity—this packing must be easily and readily applied, and it 25 has been found most expeditious and generally satisfactory to apply the same in the form of a self-hardening liquid or semi-liquid composition to the inner sides of the flanges of the covers, so that when it dries 30 it forms what is known as a “lining skin,” 35 adhering to the flange and being yieldingly compressible to perform its desired function. Furthermore, the composition should of course be non-deleterious to the contents of 40 the can, for in spite of every precaution a small portion thereof might be squeezed into the interior of the can, but even when the material is perfectly harmless it is not desirable that any portion thereof, when the 45 flanges are subjected to the forces of the seaming mechanism, be forced into the container. Therefore, several things must be 50 taken into consideration in attempting to provide a machine for applying this initially liquid or semi-liquid compound to the

flanges of can heads or covers; first, the quantity delivered must be capable of being regulated to a nicety, any excess being apt to be squeezed into the container and any deficiency being likely to prevent the formation of a perfectly air-tight seam; second, in applying the compound to each head or cover, the distribution thereof should be substantially uniform, for lack of uniformity of distribution would be subject to the same objections as the delivery of an excessive or a deficient quantity; third, any so-called “lining” machine, to be of any practical use, must have a comparatively large output capacity—that is to say, must be capable of being operated at comparatively very high velocity and yet insure uniform delivery of the proper quantity of the lining composition.

The more common type of machine at present employed for lining can heads or covers includes a conduit or passage from a suitable source of supply and which terminates in a nozzle from which the liquid or semi-liquid composition is discharged upon the edge of a head or cover rotated underneath the same, means being provided to regulate the volume of the discharge and to automatically start and stop the same at proper intervals, controlled, as a rule, by the positioning in and ejection from the machine of a head or cover underneath said nozzle. In spite of its extensive use, there are many objections to this type of machine, among which may be mentioned, first, in view of the initial consistency and the self-hardening quality of the composition employed, it is very difficult to prevent the clogging or choking up of the conduit and discharge nozzle, particularly when use of the machine has been temporarily discontinued; second, in view of the difficulty of keeping the composition in a heated condition—and the practical impossibility of keeping it at a substantially constant or uniform high temperature—it is necessary to employ in a machine of this type a composition which includes a solvent, hardening taking place upon evaporation of the solvent, which is relatively very volatile, such a composition being far less to be desired than one which liquefies upon the application of heat and hardens to a greater or lesser degree upon cooling; third, the manner in which the composition is handled or

manipulated in a machine of this type, considering the quality of viscosity inherent in the solution which it is necessary to employ, renders it practically impossible to prevent 5 the smearing of parts of the machine and the heads or covers being lined.

The present invention has in view the provision of an improved and entirely new and different type of machine for applying a 10 lining composition to can heads or covers, one of my principal objects being a machine capable of being operated at comparatively very high speed without substantial variance in the quantity of the liquid or semi-15 liquid composition delivered to each head or cover or lack of the required degree of uniformity of distribution. Incidental to the above, I have in view the provision of a machine particularly adapted for the application 20 of a composition which is a liquid or semi-liquid when in a heated state and hardens upon cooling, which, as hereinbefore suggested, is a much better composition for all practical purposes than one which includes 25 a volatile solvent. Furthermore, this invention contemplates a machine of the utmost simplicity, mechanically, dependable in operation, not likely to get out of order, readily adjustable to can heads of various 30 sizes, and with parts easily accessible for repair or replacement.

My invention will be more readily understood by reference to the accompanying drawings, forming a part of this specification, in which I have illustrated a practical and convenient embodiment of said invention, and in which—

Figure 1 is an end elevation of a machine embodying my invention;

40 Fig. 2 is a similar view of the opposite end thereof;

Fig. 3 is a perspective plan view thereof, taken as indicated by the line 3—3 of Fig. 1;

45 Fig. 4 is an enlarged transverse section of the same, taken substantially on the line 4—4 of Fig. 3, and

Figs. 5 and 6 are fragmentary sectional detail views showing the relative disposition of the curled flange edge of a cover 50 being lined and the periphery of the feed-roller, the flanges being curled to different degrees.

Referring now to the drawings in detail, I have shown a heavy supporting frame 55 which comprises the top member 7 provided with legs 8 and 9. I prefer to provide the relatively large ribs 10 and 11 on the top face of the member 7, mounted in which are the posts 12 12 and 13 13 carrying at their 60 upper ends the relatively elongated tank 14 adapted to contain a suitable lining composition in liquid or semi-liquid form.

Passing longitudinally through the tank 14 and suitably journaled in the end walls 65 thereof is the shaft 15 mounted upon which,

within the tank, is the cylinder or roller 16 so located as to dip into the liquid contents of said tank.

The feed-roller 16 is rotated from the main driving shaft 17, the latter being suitably journaled in bearings in the bracket 18 mounted on the top-member 7 of the supporting frame and having mounted thereon the stepped pulley 19 adapted to be connected in the usual manner to any suitable 75 source of power. Mounted at the other end of the shaft 17 is a pinion 20 in mesh with a gear 21 on a short shaft 22 which also carries the pinion 23 in mesh with a pinion or gear 24 on the roller shaft 15, whereby 80 the roller 16 is rotated.

Bolted to the side-wall of the tank 14 are the bracket-arms 25 and 25' at the ends of which is mounted the plate 26. At one end of the plate 26 is journaled the shaft 27 and 85 at the other end the shaft 27', these shafts carrying the pulleys 28 and 28', respectively. Around these pulleys is passed the belt 30, the inside leg of which is adapted to impinge against a can head or cover 29 interposed 90 between said belt and the roller 16, as shown in Figs. 3 and 4. In order to adapt the machine to can heads of different diameters, I have shown the plate 26 adjustably mounted on the bracket-arms 25 and 25', the latter 95 being provided with slots 31 and 32, respectively, through which pass screw-bolts 33 and 34, whereby the distance from the inside leg of the belt 30 to the roller 16 may be varied.

100 While one or the other of the pulleys 28 and 28' might be an idler, I prefer that both of the shafts 27 and 27' be driven, and for this purpose I mount upon the shaft 17 a sheave 36 for driving the rope-belt 37 which 105 passes therearound, thence around an idler sheave 38 on the shaft 27, thence under and around the sheave 39 fixed upon the shaft 27', thence over and around the sheave 40 fixed upon the shaft 27, and thence back to 110 the sheave 36.

I have shown the end walls 41 and 41' of the tank 14 with recesses in the top edges thereof which provide inclined surfaces for the support of the bar 42, which is one of a pair of track-bars, the other 43 of which is carried by the bracket-arms 25 and 25' through the interposition of the cylindrical spacers or supporting members 44 and 44'. Mounted at the ends of the track-bar 42 are 120 the bracket-arms 45 and 45' which carry the upper guide-bar 46 the lower face of which is spaced above the plane of the upper faces of the track-bars 42 and 43 a trifle more than the thickness of the usual can head or 125 cover.

130 Mounted upon one end of the track-bars 42 and 43 is the base or bottom 47 of a cover-feed chute which includes the side-guides 48 and 49, the latter being extended as shown

in Fig. 3 and serving to direct the covers between the belt 30 and the roller 16 and to engagement by the former. At the opposite end of the track-bar 42 is secured the base 5 or bottom 50 of the cover discharge chute which includes the side-guides 51 and 52, the latter being bent, as shown, to receive the heads or covers which have been advanced by the belt 30 and direct the same to said chute. It will be noted that both the feed and the discharge chutes have the same inclination as the track or run-way which comprises the bars 42 and 43.

The composition within the tank 14 may be kept at the desired high temperature in many different ways, but for purposes of explanation I have shown a gas-pipe 53, designed to be connected in the usual manner with a suitable source of fuel-gas supply and 20 provided with a series of jets or burners 54 so positioned as to direct the flames against the bottom of the tank. I have also shown a wiper or scraper 55 adjustably secured to the top of the tank and provided 25 with an edge in contact with the rotating roller 16 to remove the surplus material which adheres to said roller, so that only a comparatively thin film thereof remains.

The heads or covers being fed successively 30 into the upper end of the chute 47, it will be apparent that they will be conveyed by gravity to position between the inside leg of the belt 30 and the periphery of the roller 16. The belt 30 being yielding, the edge of 35 the cover will be pressed against the rotating roller and at the same time the cover will be revolved to convey the same along said roller in the direction of the discharge chute 50. During such rotative advancement of the cover, the edge of the curled flange 56 will scrape from the rotating roller 16 a certain amount of the composition in the form of a film thereon, the composition being uniformly deposited along said flange 40 within which it adheres to provide the usual "lining skin" for the purposes set forth.

The flanges of can heads or covers adapted to be secured to body portions by the double-seaming process are sometimes received 45 tangentially bent or turned, as shown in Fig. 5, and sometimes have the edges thereof inturned, as shown in Fig. 6. In either case, the disposition of the cover, supported upon the track-bars 42 and 43 and below the 50 guide-bar 46, relative to the periphery of the roller 16 is such that the extreme edge only of the flange contacts with the roller, and with the wiper or scraper 55 properly adjusted no composition will touch the 55 cover elsewhere than within the flange-groove, in consequence of which the belt 30 will be kept clean and there will be no smearing of any of the parts of the machine.

I have found from experience that the 60 machine of my present invention may be

operated with great rapidity, and yet the composition will be properly and uniformly delivered to the desired position within the flange. In fact, proper delivery of the composition is insured with the machine running as rapidly as it is possible to feed heads or covers into the chute 47. In fact, it is essential to best results that the belt 30 be driven at such velocity that the speed of the cover being delivered thereto is accelerated thereby, whereby the covers, which impinge against and support each other in the chute 47, are suitably spaced apart during transit along the cylinder or roller 16.

Many modifications of minor details of my improved machine for applying a seam-packing to can covers will doubtless readily suggest themselves to those skilled in the art to which it appertains, and I therefore do not desire to limit my invention to the specific construction herein shown and described.

I claim as new and desire to secure by Letters Patent:

1. In a machine for applying a seam-packing composition to can covers, the combination, with a rotating cylinder and means for applying to the cylindrical face thereof a substantially uniform liquid film or coating, of a slideway paralleling said cylinder and adapted to support a can end or cover through a flat side thereof with its edge directed against said cylinder, means for pressing said cover edgewise against said cylinder and at the same time imparting rotary movement to said cover whereby it is rolled along said cylinder, and a guideway chute for directing gravity-actuated covers successively to said slideway and between said cylinder and said rotating means.

2. In a machine for applying a seam-packing composition to can covers, the combination, with a rotating cylinder and means for applying to the cylindrical face thereof a substantially uniform liquid film or coating, of a slideway paralleling said cylinder and adapted to support a can end or cover through a flat side thereof with its edge directed against said cylinder, yielding means for pressing said cover edgewise against said cylinder and at the same time imparting rotary movement to said cover whereby it is rolled along said cylinder, and a guideway chute for directing gravity-actuated covers successively to said slideway and between said cylinder and said rotating means.

3. In a machine for applying a seam-packing composition to can covers, the combination, with a rotating cylinder and means for applying to the cylindrical face thereof a substantially uniform liquid film or coating, of a slideway laterally inclined toward said cylinder and extending substantially the length thereof whereby the edge of an obliquely-disposed can cover on said slide-

- way is directed against said cylinder, means for pressing said cover edgewise against said cylinder and at the same time imparting rotary movement to said cover whereby it is 5 rolled along said cylinder, and a guideway chute for directing gravity-actuated covers successively to said slideway and between said cylinder and said rotating means.

4. In a machine for applying a seam-
10 packing composition to can covers, the combination, with a rotating cylinder and means for applying to the cylindrical face thereof a substantially uniform liquid film or coating, of a slideway laterally inclined toward 15 said cylinder and extending substantially the length thereof whereby the edge of an obliquely-disposed cover on said slideway is directed against said cylinder, yielding means for pressing said cover edgewise 20 against said cylinder and at the same time imparting rotary movement to said cover whereby it is rolled along said cylinder, and a guideway chute for directing gravity-actuated covers successively to said 25 slideway and between said cylinder and said rotating means.

5. In a machine for applying a seam-
30 packing composition to can covers, the combination, with a rotating cylinder and means for applying to the cylindrical face thereof a substantially uniform liquid film or coating, of a slideway paralleling and slanted toward 35 said cylinder and extending substantially the length thereof whereby the edge of an obliquely-disposed cover on said slideway is directed against said cylinder, means for 40 pressing said cover edgewise against said cylinder and at the same time imparting rotary movement to said cover whereby it is rolled along said cylinder, and a guideway chute for directing gravity-actuated covers successively to said slideway and between 45 said cylinder and said rotating means, said guideway being disposed at an angle to and in the plane of said slideway, and the velocity of the driven rotating means being proportioned relative to the inclination of 50 said chute to exceed the speed of delivery of covers from said chute whereby said covers are spaced apart during the composition-applying operation.

6. In a machine for applying a seam-
55 packing composition to can covers, the combination, with a rotating cylinder and means for applying to the cylindrical face thereof a substantially uniform liquid film or coating, a slideway paralleling said cylinder and 60 extending substantially the length thereof whereby the edge of a cover on said slideway is directed against said cylinder, means for pressing said cover edgewise against said cylinder and at the same time imparting rotary movement to said cover whereby it is rolled along said cylinder, and a guideway chute for directing gravity-actuated 65 covers successively to said slideway and between said cylinder and said rotating means, the velocity of the driven rotating means being proportioned relative to the inclination of said chute to exceed the delivery of covers from said chute, whereby said covers are spaced apart during the composition-applying operation.

7. In a machine for applying a seam-pack-
70 ing composition to can covers, the combination, with a rotating cylinder and means for applying to the cylindrical face thereof a substantially uniform liquid film or coating, of a slideway paralleling and slanted toward 75 said cylinder and extending substantially the length thereof whereby the edge of an obliquely-disposed cover on said slideway is directed against said cylinder, means for 80 pressing said cover edgewise against said cylinder and at the same time imparting rotary movement to said cover whereby it is rolled along said cylinder, and a guideway chute for directing gravity-actuated covers successively to said slideway and between 85 said cylinder and said rotating means, said guideway being disposed at an angle to and in the plane of said slideway, and the velocity of the driven rotating means being proportioned relative to the inclination of 90 said chute to exceed the speed of delivery of covers from said chute whereby said covers are spaced apart during the composition-applying operation.

8. In a machine for applying a seam-pack-
95 ing composition to can covers, the combination, with a rotated cylinder and means for applying to the cylindrical face thereof a substantially uniform liquid film or coating, of a slideway paralleling said cylinder and 100 extending beyond each end thereof, said slideway being adapted to support a can end or cover through a flat side thereof with the edge directed against said cylinder, a pulley-driven endless belt paralleling said slideway on the side thereof opposite said cylinder and adapted to engage the edge of a cover and roll the latter along said cylinder, and means for delivering covers successively to said slideway between one end of said cylinder and the belt-carrying pulley at that end thereof, whereby each cover is subjected to yielding forces only during advancement 105 thereof.

In testimony of the foregoing, I have here-
115 unto set my hand in the presence of two
witnesses.
